FEED DRUM ADJUSTING MECHANISM

Augustus J. Richards, Lakewood, Ohio, assignor to Bonnar-Vawter, Incorporated, Cleveland, Ohio, a corporation

Application May 3, 1954, Serial No. 426,977

7 Claims. (Cl. 271—2.6)

This invention relates to feed drum adjusting mechanism and particularly to such mechanism which ordinarily comprises important elements in collating machines.

In such machines, where webs of paper are brought together and must be kept in alignment and register, perforations are generally present in each web at the edge thereof, so that pins on feed drums of the machine may enter and not only assist in tensioning the web for withdrawal from the storage rolls but also to keep the printed matter on the web faces in register.

Inasmuch as the length of the web is affected by many conditions, such as moisture content of the paper, whereby one web may actually be slightly longer in places than the other, accurate feed hole registration as between webs is disturbed. This may not only cause a buckling of the web but under certain conditions a tearing of the web might result in compelling shutdown of the machine.

Heretofore it has not been possible to compensate for such changes as above indicated without shutdown and thus valuable productive time is lost.

Even if the machine is shut down, the adjustment of the feed drums must be effected by wrenches in a laborious manner, and further trial and error is the basis on which such adjustment is made, further causing constant starting and stopping of the machine to determine if the adjustment has been properly made.

It will be apparent that this present manner of resorting to adjustment of such feed drums consumes time and delays the resumption of production which on machines of the type to which this invention is directed is carried out at relatively high speed, and thus delays are desirable to be obviated.

Thus if the foregoing problems can be obviated and a substantial increase in production may be effected a substantial advance will have been made in the art, and this is one of the primary purposes and accomplishments of this invention.

A further principal object of the invention is to provide feed drum adjusting mechanism which is simple in mechanical construction, and may be incorporated in such machines with a minimum amount of rearrangement of the various components thereof.

It is a further object of this invention to enable feed drums to be adjusted in collating machines, while the machine is operating preventing the loss of time usually accompanying such adjusting manipulation.

Yet a further object of the invention is to provide a feed drum adjusting mechanism which is readily accessible and with very little previous skill may be operated so as to cause the adjustment to take place while the machine is in operating action, the various parts thereof being simply arranged for such manipulation.

A further object of the invention is to provide a feed drum adjusting mechanism which will compensate both for misalignment of the feed pins with respect to the web moving thereover, in longitudinal fashion, and in

2

addition change the relative rotative relation of the shaft and drum, both of the foregoing being accomplished while the machine is in operation.

A still further object of the invention is to provide a feed drum adjusting mechanism which may be readily fitted at the end of a feed drum and thus accessible for the operator of the machine, which includes easily manipulable hand wheels, one of the same regulating rotative relation of the shaft and drum carried thereby, and the other moving the drum on the shaft at right angles to such rotative change.

Other and further objects of the invention will be understood from a consideration of the specification appended hereto and shown in the drawings wherein Figure 1 is a diagrammatic illustration of the general arrangement of feed drums in a collating machine of the type with which this invention may be associated.

Figure 2 is a fragmentary enlarged view, partly in section, showing the general arrangement of the adjusting mechanism for one of the feed drums in a collating machine.

Figure 3 is an end view of a feed drum including certain of the adjusting elements, one of the hand wheels usually associated therewith being omitted, and showing the various parts in different positions.

Figure 4 is a sectional view taken about on the line 4—4 of Figure 3 looking in the direction of the arrows, illustrating more particularly the manner of effecting movement of certain of the parts.

Figure 5 is a sectional view taken about centrally and longitudinally of a feed roll such as is intended to be used with this invention, illustrating more completely certain of the parts for effecting movement of the feed roll inwardly and outwardly on the shaft of the machine.

Referring now to the drawings, Figure 1 illustrates diagrammatically certain portions of a collating machine, a substantial number of the usual parts being omitted, showing the feed rolls 1, as having extending from their peripheries the usual feed pins 2. As will be understood the feed rolls desirably have their axes in parallelism and are fixed relative to one another. Thus their peripheries are tangentially in the same plane also so that the webs 3 being withdrawn from the storage rolls 4 may be brought into juxtaposition after having passed over the usual tensioning rolls 5 and 6. As will be further understood, the webs 3 are provided at at least one edge with suitable perforations, spaced to correspond with the spacing of the pins 2 on the drum 1 so that register of the printed matter which may appear on the face of the webs may be maintained, and alignment of the webs one with the other may likewise be maintained. It should also be pointed out that under certain conditions one of the webs 3 may be slightly longer or shorter than the other web and thus the portion 7 of the web 3 may either buckle or be overly tensioned as is well known. It is thus desirable to effect adjustment of the feed roll 1 at the right hand side of Figure 1, to prevent misregister or misalignment of the web. This adjustment may be affected by the mechanism to be more particularly described in reference to the other figures in the drawings.

Turning therefore to a consideration of the Figures 2, 3, and 4, the feed drum 1 is shown as being comprised of a cylindrical or tubular member 8, of substantial length susceptible of supporting thereon a web of any suitable width, and as shown in Figure 5 is equipped at or near one end with a spacer 9 of disc-like configuration, closely fitting the interior of the tubular drum 8 and fastened thereto as by means of the screws 10.

A similar disc-like member 11 is provided at or near the other end of the drum 8, and likewise fastened as by

means of the screws 12. The whole drum is supported on the shaft 13, which is intended to be driven in any suitable manner, the support being in the form of a frame 14, and the shaft being carried in the frame as by means of the bearing 15, it being apparent that other bearings may be provided on the shaft so as to maintain the same in alignment for rotation and drive in any suitable manner.

Reference will now be had particularly to Figures 3 and 4, the same showing the shaft 13 as being equipped with a suitable keyway 16, the keyway 16 in turn being adapted to receive a key 17 therein, which key is likewise engaged with a bronze bushing member 18. The bronze bushing member 18 provides for relative rotation of the disc-like member 11 with respect to the shaft, the disc 9 being mounted loosely on the shaft likewise so as to permit relative rotation of the shaft and the drum supported by the discs 9 and 11.

In order to effect a driving of the drum in a rotative manner by means of the shaft 13, the mechanism now to be described is resorted to. This mechanism includes a generally rectangular drive plate 19, as shown in both dotted and full lines in Figure 3, which drive plate 19 is pressed or otherwise suitably non-rotatively fitted on the bronze bushing 18 close to the face of the disc-like member 11.

Fastened at a suitable pivot point 20, to the drive plate 19, is the drive arm 21, the same being equipped at its lower end as viewed in Figure 3 and shown particularly in Figure 4 with a cam member 22, suitably fastened to the arm 21 by means of the bolts 23. The other end of the drive arm 21 is provided with a roller 24, pivotally supported at 25 on the said end of the arm, and adapted to engage a drive member 26 fastened to the disc-like member 11 as by means of a bolt 27, the said drive member in this instance constituting a roller.

Fastened to the other face of the drive plate 19 is a threaded sleeve 28, the same being equipped with flange 29, whereby the sleeve 28 may be fastened as by means of the machine screws 30 to the drive plate 19. Mounted so as to engage the threads of the sleeve 28 is a cam member 31, cam member 31 being tapered as at 32, so as to engage the cam member 22 on the lower end of the drive arm 21 as seen in Figure 4. The cam member 31 is thus a conical member in essence, and in turn is suitably equipped with a hand wheel 33, fastened by means of the machine screws 34 to the said cam member 31.

It will thus be understood that when the cam member 31 under the control of the hand wheel 33 is moved on the threads of the sleeve 28, it will engage the cam member 22, and change the angular relation between the drive arm 21 and the drive plate 19. In order to maintain the roller 24 of the drive arm 21 in contact with the drive member 26, suitable springs 35 are provided for connecting the member 11 and plate 19 on which arm 21 is carried, the same being fixed by means of the studs 37 to the drive plate 19 as seen in Figure 3, and at their opposite ends to the disc-like member 11 on the studs 38.

As seen in Figure 3, in full lines the angular relationship between the drive plates 19 and 21 has been altered so that the relative rotative relation of the shaft 13 and the pins 2 of the drum 1, has thus been changed also. It will be apparent that by moving the hand wheel 33 inwardly or outwardly such adjustment of the relative rotative relation of the shaft 13 and pins 2 may be changed at will and this may be accomplished while the drum is rotating by grasping and holding the hand wheel, permitting the shaft to turn with respect thereto and causing the cam 32 to ride against the cam section 22 of the arm 21 and cause the said arm and plate to change their relationship. This will of course cause an abutment of the roller 24 with the drive member 26 fixed on the member 11 and thereby to the drum, whereby the adjustment is effected.

In Figure 3, the parts 19 and 21 are shown in full lines in one position, the dotted lines another position to which the same may be moved and thus change the rotative relation of the shaft 13 and drum 8. The pins 2 are shown in corresponding full and dotted lines. The position of the parts 21 and 22 in Figure 4 correspond to the dotted line locations thereof in Figure 3, the cam 31 being likewise in the corresponding position.

The foregoing compensates for buckling of the web by reason of the lack of tension therein, and also can compensate for an over-tensioning of the web which might tend to tear the same and particularly the feed hole section therein.

In order to accomplish changes in the longitudinal alignment of the pins 2 of each of the respective drums 1 as shown in Figure 1, further adjusting parts are provided, and shown more particularly in Figures 4 and 5. These parts comprise a stud 40, suitably threadedly engaged at 41 with the end of the shaft 13, and maintained in that position by a lock nut 42. A suitable cap 43 is provided through which the stud 40 extends, the outer end of the stud being threaded at 45, and equipped with a hand wheel such as 46. The foregoing taken in conjunction with the disclosure in Figure 5 illustrates the manner of effecting the adjustment wherein a spring unit 47 is provided, bearing at one end in a suitable member 48, the member 48 being in turn carried on the bearing 15. At the other end the spring 47 engages a suitable cup-like member 49, which in turn bears against the face of the disc-like member 9 as will be understood. In manipulating the hand wheel 46, by rotating the same in one direction, it will be apparent that the entire cylinder 1 may be moved for example toward the right, by causing the hand wheel to move on the stud 40 toward the right on the threads provided, thus tensioning the spring 47 still further. Conversely, when the hand wheel 46 is rotated in the opposite direction, the spring 47 may expand and move the drum back to the position as for example that shown in Figure 5.

There is thus provided a simple adjusting means for the feed drum of a collating machine or the like, whereby during actual rotation of the drum or drums as the case may be the respective hand wheels 33 and 46 may be manipulated so as to accomplish both rotative changes of the feed pins carried by the drums with respect to the shaft, and also to move the drum inwardly and outwardly on the shaft toward the frame for example to carry out necessary aligning of the respective webs of paper being manipulated or driven thereby.

I claim:

1. In drum adjusting mechanism of the class described in combination, a frame, a drive shaft carried thereby, a drum mounted thereon and means for driving said drum comprising, a drive plate fixed to the shaft, a drive arm pivotally mounted on said plate, a drive member connected to the drum engaged by the drive arm, and cam means shiftable relatively to the drum likewise engaging the drive arm aforesaid to pivot the same on the plate whilst in engagement with the drive member mentioned and rotate the drum relatively to the shaft.

2. The combination as claimed in claim 1, wherein a cam element is provided on the drive arm for co-operation with the cam means, and resilient means are provided for maintaining the arm in engagement with the drive member mentioned.

3. In drum adjusting mechanism of the class described, in combination, a frame, a drive shaft carried thereby, a drum mounted thereon, and means for driving said drum by said shaft comprising a drive plate connected to the shaft, a drive arm pivoted intermediate its ends on said plate, a cam member shiftable on the shaft and engaging the arm aforesaid to vary the rotative relationship of said arm and plate, said arm being likewise adapted to engage a drive member connected to the drum, the arrangement being such that variation in the rotative

relationship of the arm and plate will correspondingly vary the rotative relationship of the drum and shaft.

4. The combination as claimed in claim 3, wherein resilient connections between the drive plate and drum are arranged to maintain the drive arm in engagement with the cam member and the drive member.

5. The combination as claimed in claim 3, wherein the means for driving the drum include a bushing mounted on the shaft for rotation therewith and movement therealong, said bushing is fixed to the drive plate, and means are provided at one end of the shaft to effect relative movement of the shaft and bushing as stated, and thereby the drum mounted on the shaft.

6. In drum adjusting mechanism of the class described, in combination, a frame, a drive shaft carried thereby, a drum carried on the shaft and having a series of pin members on its periphery, and means accessible at one end of the drum for shifting the same along the shaft and rotatively with respect thereto, during rotation on the said shaft, to change the position of the pin members

with respect to the shaft, said shifting means including a drive plate connected to the shaft, a drive arm mounted on said plate engaging a drive member connected to the drum, a hand wheel supported on the shaft, and cam elements operable by said wheel for moving the drive plate with respect to the drive arm, whereby the drive member is rotated with respect to the shaft.

7. The combination as claimed in claim 6, wherein said shifting means further include a second hand wheel carried by the shaft, a screw member carried by the shaft engaged by said wheel for moving the drum along the shaft, and resilient means carried on the shaft opposing said movement.
